UNITED STATES PATENT OFFICE.

THOMAS C. WHITEHEAD, OF DETROIT, MICHIGAN.

COOLING SYSTEM FOR REFRIGERATING APPARATUS.

Application filed November 19, 1923. Serial No. 675,638.

This invention relates to refrigerating apparatus and refers more particularly to means for cooling the compressor and radiator thereof to facilitate the cooling and condensing of the compressed refrigerating medium.

An object of the invention is to provide a compact and efficient apparatus in which a device for compressing a refrigerating medium is preferably located between a radiator for receiving the compressed medium, and a fan for drawing air through the radiator to cool the same and the compressor.

Another object is to provide an apparatus in which the radiator, compressor and fan are preferably arranged in alignment with a motor upon a suitable support and are preferably enclosed by a light and durable hood that co-operates with the support to form a passage for directing the air drawn through the radiator against the compressor.

With the above and other objects in view, the invention consists of certain novel features of construction, combination and arrangement of parts as will be more fully described and particularly pointed out in the appended claims.

In the accompanying drawing:

Figure 1 is a side elevation of a hood embodying my invention enclosing a radiator, compressor and fan of a refrigerating apparatus;

Figure 2 is a perspective view of the hood; Figure 3 is an end elevation thereof.

Figure 4 is a perspective view of the support on which the refrigerating apparatus is mounted.

Referring now to the drawing in which like characters of reference designate corresponding parts throughout the several views, the numeral 1 designates a stand having a flat top 2 upon which I preferably mount a pump 3 for compressing a refrigerating medium, a motor 4 having a shaft 5 for driving the pump, and a radiator 6 having a series of coils 7 through which the compressed medium passes to be cooled and condensed before entering the usual brine tank (not shown) of a refrigerator. The coils 7 of the radiator are preferably arranged in superposed relation within a frame 8 and are preferably spaced apart as shown so that air from the atmosphere may circulate freely therebetween. The uppermost coil 9 is pref-

erably connected by a suitable tube 10 to the exhaust conduit 11 of the pump while the lowermost coil 12 is preferably connected to a tube 13 that leads to the usual float chamber (not shown) on top of the brine tank.

To facilitate the cooling and condensing of the compressed medium passing through the coils 7 of the radiator, I preferably provide a suitable fan 14 that is mounted on the motor drive shaft 5 to be driven thereby for drawing air through the radiator to cool the same and the pump. For directing the air drawn through the radiator by the fan against the compressor, the radiator 6, pump 3 and fan 14 are preferably arranged in alignment on the stand 1 and are enclosed by a hood 15 that fits the radiator casing 8 and that cooperates with the top 2 of the stand to form a passage from the radiator to a point slightly beyond the fan. The hood 15 may be constructed of any light and durable material such as sheet metal and is preferably provided at its lower edges with laterally extending flanges 16 that are detachably secured to the top 2 of the stand.

In order that the hood will fit the radiator casing 8 snugly, I preferably provide outwardly projecting top and side flanges 17 and 18 respectively at one end of the hood for embracing the radiator casing 8. The top flange 17 is preferably provided at spaced points with elongated openings 19 to receive screws 20 or other suitable securing elements for clamping the hood to the radiator casing, while between the openings 19 is an elongated opening 21 for receiving the tube 13 and the usual tubing extending between the brine tank (not shown) and the pump.

As shown in Figure 2, the hood is preferably provided with a substantially V-shaped portion 22 at the top that inclines gradually downwardly from the flange 17 to the rear end of the hood, while upon opposite sides of the V-shaped portion 22 are transversely curved substantially triangular shaped portions 23 that connect into the rearwardly converging sides 24 of the hood.

From the foregoing description it will be apparent that I have provided a single means for cooling effectively both the radiator and the compressor. Thus, complete condensation of the refrigerating medium is assured before it reaches the usual brine tank in a refrigerator. In addition to cooperating

with the top 2 of the standard to form a passage for directing the air drawn through the radiator toward the compressor the hood 15 also serves as an efficient guard for the 5 fan 14.

While it is believed that from the foregoing description the nature and advantages of the invention will be readily apparent, I desire to have it understood that I do not 10 limit myself to what is herein shown and described and that such changes may be resorted to when desired as fall within the scope of what is claimed.

What I claim as my invention is:—

15 1. In a refrigerating apparatus, the combination with a pump for compressing a refrigerating medium, a radiator for condensing the compressed medium, a motor for driving said pump, and a fan operatively connected to said motor, of a removable housing enclosing said pump and fan provided with an opening at one end thereof of an area corresponding to the area of the radiator and having a substantial arcuate-shaped opening at the opposite end thereof of substantially the same area as said fan and motor.

20 2. In a refrigerating apparatus, the combination with a pump, a radiator, and a motor, of a common portable support therefor, a relatively short driving shaft between said pump and motor, a fan on said shaft for effecting a circulation of air through the radiator and around the pump, 35 and a removable inverted trough-shaped hood covering said radiator, pump and fan and having openings at the opposite ends thereof, the opening at the forward end thereof receiving said radiator and substantially corresponding in shape and area to the vertical rear face of said radiator, the opening at the rear end of said hood substantially corresponding in shape and area to the vertical cross sectional area of said 40 motor, the upper wall of said hood extending downwardly and rearwardly from the opening at the forward end of said hood to a point adjacent to the opening at the rear end thereof and the side walls of said hood 45 converging from the opening at the forward end thereof to a point adjacent to the opening at the rear end thereof whereby air from the radiator will be directed by said hood

downwardly and inwardly toward said motor. 55

3. In a refrigerating apparatus, a pump for compressing a refrigerant, an air cooled radiator adjacent said pump and in which the compressed refrigerant is adapted to be 60 condensed, a motor adjacent said pump for driving the same, a relatively short drive shaft extending between said motor and pump whereby said pump is driven directly by said motor, and a hood extending over 65 said radiator and pump, the forward end of said hood having an opening for receiving said radiator and substantially corresponding in shape to the vertical rear face of said radiator and the rear end of said hood having an opening substantially corresponding 70 in shape and area to the vertical cross sectional area of said motor, said openings being in substantial alignment whereby air entering the hood from the radiator will flow against and around the pump and will 75 flow against and around said motor.

4. In a refrigerating apparatus, a pump for compressing a refrigerant, an air cooled radiator adjacent said pump and in which the compressed refrigerant is adapted to be 80 condensed, a motor adjacent to said pump for driving the same, a relatively short drive shaft extending between said motor and pump whereby said pump is driven directly by said motor, a fan on said shaft, and 85 a relatively straight inverted trough-shaped open ended hood extending over said radiator pump and fan whereby air will be drawn by said fan through said radiator and around said pump toward said motor, the opening at the forward end of said hood receiving said radiator and substantially 90 corresponding in shape to the vertical rear face thereof, and the opening at the rear end of said hood being smaller than the 95 opening aforesaid and substantially corresponding in shape and area to the vertical cross sectional area of said motor, the top wall of said hood inclining downwardly from the forward end thereof to the rear end thereof whereby air entering said hood from said radiator will be drawn by said fan over said pump and will be directed downwardly 100 toward said motor.

In testimony whereof I affix my signature.
THOMAS C. WHITEHEAD.
